E. Elmira J. Key, of Lowell, Mass.

DES. 1925

Assign to

The Lowell Manufacturing Company, of same place.

Letters Patent No. 1925 - Dated March 22nd 1864.

Design for a Carpet Pattern.

The schedule referred to in these Letters Patent and making part of the same.

To all whom it may concern:

Be it known that I, Elmira J. Key, of Lowell, in the County of Middlesex and State of Massachusetts, have originated and designed a new Pattern for Carpets or other fabrics, of which the following is a full, clear and exact description, reference being had to the accompanying drawings, making part of this specification.

In corner A, is one fourth of a ground composed of small blocks, surrounded by the double frame 1. Figure B, which is composed of a ground of parallel lines enclosed by a triple frame, is partially overlapped by the frame 1. Bands 3 and 3 are halves of figures composed of zig-zag lines.

The figures and surroundings of corner C, are similar to those of corner A. The parallel bands 4 and 5, connect the figures of corners A and C, and are composed of successions of parallel lines, said bands being bordered on the outer edge by the irregular work 6. 7. Lying between bands 4 and 5, is the flower 8, surrounded by leaves and sprigs in outline. The remainder of the design is occupied by the ground work D, D, which is composed of a number of small blocks (each supporting a small cross), the space not occupied by the blocks being filled with light, mottled work.

The colors employed for the different portions of the design, may be varied to suit the taste and wish of the manufacturer.

Claim.

What I claim as my invention and desire to secure by Letters Patent, is, The design or Pattern for Carpets or other fabrics, herein set forth.
